Attorneys.

UNITED STATES PATENT OFFICE.

NORMAN ISACHSON, OF ALBION, IDAHO.

ENGINE-TIMER.

1,397,005.

Specification of Letters Patent.

Patented Nov. 15, 1921.

Application filed March 30, 1920. Serial No. 369,934.

To all whom it may concern:

Be it known that I, NORMAN ISACHSON, a citizen of the United States, and a resident of Albion, in the county of Cassia and State 5 of Idaho, have invented certain new and useful Improvements in Engine-Timers, of which the following is a specification.

This invention relates to spark timing apparatus for use in internal combustion engines, and is designed more particularly for use in connection with Ford engines, though not limited to such use.

The invention aims to provide a construction which will be free from the detrimental 15 effects of the lubricating oil which works out from the cam shaft bearings, and further to so construct and arrange the parts that the play due to wear on the cam shaft will not affect the proper timing action.

20 With these and other objects in view, the invention includes the novel features of construction and arrangement and combination of parts hereinafter described and particularly defined by the appended claims.

25 An embodiment of the invention is illustrated in the accompanying drawings in which:

Figure 1 is a face view of the timer.

Fig. 2 is a transverse section showing it 30 in operating position relative to the operating shaft and engine frame which are shown broken away.

Figs. 3 to 7 are views of details.

Referring by reference characters to this 35 drawing, the numeral 1 designates the engine frame and 2 the timer shaft or cam shaft by which the rotor of the timer is carried. 3 designates the commutator or timer shell which is made of customary material 40 and which is provided with a cylindrical portion 3^a which fits within or abuts against an annular flange 1^a on the face plate or part 1 of the engine. The outer portion of the shell is preferably made of approxi- 45 mately conical shape as shown, and is provided at its outer extremity with a seat or bearing section 3^b which is engaged by the usual clamp arm 4 to hold the shell in position. Within the cylindrical portion of the 50 shell, I place an annular lining sleeve or band 5 and inside of this a fiber ring 6, fiber being specified as the preferred insulating material, though other material may be used if desired without departing from the spirit 55 of my invention. This fiber ring 6 is provided with recesses 6^a in its face to receive

the contact members 7 which are arranged equidistant from each other and correspond in number to the number of cylinders of the engine, four being shown as the number required for a Ford engine and as an example. These contact members are preferably provided with lips 7^a which overlap the inner face of the ring 6 and they are provided with threaded holes 7^b which receive the 60 screws 8 which serve to hold the contact members and fiber ring in position and also to connect the conductor wires.

The screws are provided preferably with knob heads 8^a as shown to enable them to be 65 conveniently operated, and they are provided with fiber washers 9 to insulate them from the shell. Upon the end of the cam shaft 2 I place a collar or sleeve 10 which is keyed thereon by a pin 11 engaging a slot 70 10^a in the collar and a corresponding hole in the cam shaft, the key or pin being held in place by a cupped washer 12 interposed between the sleeve and the nut 13 applied to the end of the cam shaft. This sleeve may 75 conveniently and economically be made by bending a piece of sheet metal into cylindrical form, the edges having two marginal flanges which are riveted together and form a flange 10^b. Longitudinal cuts are made in the opposite side of the sleeve and the portion of the wall of the sleeve between these cuts is bent outward at right angles as shown at 80 10^c to form a lug or projection the end of which is shaped to form a bearing *d* for one arm 85 of the yoke hereinafter described.

The flange 10^b opposite this projection is cut away and the cut away face is provided with a bearing *d'* for the other arm of the yoke. The yoke is shown at 14 and comprises a substantially semicircular body portion, bent up preferably from sheet metal and having the extremities of the arms thereof provided with openings to receive the bearing projections or bosses *d*, *d'* of the 90 sleeve. The arm on the flange side of the sleeve is provided with a projection 14^a which coats with the non-cut-away portion of the flange 10^b and thereby serves as a stop to limit the swinging movement of the yoke 100 under the action of the compression spring 15 which is located between a projection 10^c on the sleeve and a projection 14^a on the yoke, it being understood that the stop is to hold the yoke in position convenient for 105 assembling. The upper part of the yoke carries a brush or contact member 16 which is 110

preferably formed integral with the yoke, conveniently by bending up a T-shaped tongue or projection into perpendicular position, the head of the T being recessed to 5 receive a contact member or plate 16^a having a rounded face designed to coact with the contact member 7, this contact plate being secured by a rivet *a* of relatively soft metal which can be easily cut when the plate 10 is worn and needs to be replaced. Instead of using a binding screw engaging a threaded opening in the contact member, I may form the screw 7^c as an integral part of the contact 7 and use a binding nut 8^x as shown 15 in Fig. 4.

Having thus described my invention, what I claim is:

1. In a spark timing device, the combination with the timer shaft, of a sleeve on 20 said shaft, a yoke pivoted on the sleeve, a spring acting on said yoke, said sleeve having a lug or projection and said yoke a part coöperating with said projection to limit the movement of the yoke, a brush carried by 25 said yoke, a timer casing encircling the shaft, and a plurality of contacts carried by said casing and coöperating with said brush.
2. In a spark timing device, the combination with the timer shaft of a sleeve on said 30 shaft comprising a sheet of metal bent to sleeve form with the edge portions in the shape of abutting flanges secured together, the opposite sides of said sleeve having bearing 35 projections, a yoke having arms pivoted

on said projections, a spring acting on said 35 yoke, a brush carried by said yoke, and a timer casing encircling said shaft and carrying contacts.

3. In a spark timing device, the combination with the timer shaft of a sleeve on said 40 shaft comprising a sheet of metal bent to sleeve form with marginal portions in the shape of abutting flanges secured together, said flanges having a cut-away portion with a pivot projection, an outwardly turned integral portion on the opposite side of said 45 sleeve carrying a pivot projection, a yoke pivoted on said projections, a spring acting on said yoke, a brush carried by said yoke, and a plurality of annularly arranged contacts with which said brush coacts.

4. In a spark timing device, the combination with the timer shaft, of a brush pivotally supported from said shaft and disposed in a plane substantially perpendicular thereto, a spring acting on said brush, a timer 55 casing having a cylindrical portion surrounding said shaft, an insulating sleeve within said cylindrical portion, a ring within said sleeve having recesses in its face, contacts located in said recesses and having lugs 60 overlapping the inner face of the ring, and binding screws passing through the insulating sleeve and cylindrical portion for holding the contacts and ring in position.

In testimony whereof I affix my signature.

NORMAN ISACHSON.
